H. E. ROGERS

SASH LOCK

Filed Nov. 16, 1921

Inventor:

H. E. Rogers
By Cook & McCauley Miss.

Patented June 3, 1924.

UNITED STATES PATENT OFFICE.

HARRY E. ROGERS, OF ST. LOUIS, MISSOURI, ASSIGNOR OF ONE-HALF TO JOHN O'NEAL,
OF ST. LOUIS, MISSOURI.

SASH LOCK.

Application filed November 16, 1921. Serial No. 515,442.

To all whom it may concern:

Be it known that I, HARRY E. ROGERS, a citizen of the United States of America, a resident of the city of St. Louis and State 5 of Missouri, have invented certain new and useful Improvements in Sash Locks, of which the following is a full, clear, and exact description, reference being had to the accompanying drawings, forming a part of

10 this specification.

This invention relates to improvements in sash locks, and more particularly to a locking device adapted for use on a window having an upper sash and a lower sash. The 15 main object of the invention is to produce a strong, simple and inexpensive sash lock that can be easily and quickly applied to a window. A further object is to produce a lock of this kind whereby the upper and lower 20 sashes can be forced toward each other.

With the foregoing and other objects in view, the invention comprises the novel construction, combination and arrangement of parts hereinafter more specifically described 25 and illustrated in the accompanying drawings wherein is shown the preferred embodiment of the invention. However, it is to be understood that the invention comprehends changes, variations and modifications which 30 come within the scope of the claims hereunto appended.

Fig. I is a vertical section illustrating portions of a window equipped with a sash lock embodying the features of this invention.

35 Fig. II is a front elevation showing the sash lock applied to a window.

Fig. III is a horizontal section on the line III in Fig. II.

40 Fig. IV is a perspective view showing the tubular bolt-receiving member and one end of the locking bolt associated therewith.

A designates an upper sash provided with a bottom rail 1 and a stile 2. B designates a lower sash having a top rail 3 and a stile 4. As shown by Figs. I and II, the window 45 casing C is provided with the usual vertical guideways for the sashes.

The locking device comprises a tubular 50 guide or bearing 5 having side flanges 6 seated on the top of the lower sash and secured thereto by means of screws 7 which pass through said flanges. A locking bolt 8 is slidably mounted in the guide 5 and provided with a lateral projection 9 adapted to 55 extend through a longitudinal slot 10 in the

guide 5. A transverse slot 10' is formed in the tubular guide 5 so as to communicate with the slot 10, and the projection 9 is movable in an angular path, or passageway, formed by said slots 10 and 10'. As shown 60 by Fig. I, the slot 10 is open at the inner end of the tubular guide 5, so the locking bolt can be easily applied to said guide, and when the device is secured to a window the bolt cannot be withdrawn from the guide. 65

D designates a bolt-receiving member, or keeper, in the form of a tube preferably located in the stile of the upper sash A and adapted to register with the bolt 8. This tube is provided with coarse, external screw 70 threads extending from one of its ends to the other and adapted to be screwed into the upper sash. This sash can be drilled, or bored, to receive the tube D, and said tube can then be very easily screwed into the sash, 75 as will be hereafter described. The outer end of the tube D is preferably flush with the inner face of the sash.

As shown most clearly by Figs. I and IV, the tube D is provided with an angular slot 80 11 adapted to receive a lateral projection 12 extending from the bolt 8. A portion of this slot is parallel with the longitudinal slot 10 in the guide 5, as shown by Fig. I, and this portion of slot 11 is open at the exposed end 85 of tube D, so the projection 12 can pass into and out of slot 11.

The projection 9 forms an operating handle for the locking device, and this projection can be moved from the vertical position shown by full lines to the horizontal position shown by dotted lines. It can also be moved longitudinally of the slot 10 when it occupies the horizontal position. It will therefore be understood that one end of the 95 locking bolt 8 can be readily inserted into and removed from the tube D.

When the projection 10 is moved upwardly from the position shown by dotted lines to the position shown by full lines, the 100 bolt 8 is turned and its projections 9 and 12 cooperate with the tubular members 5 and D to force the sashes toward each other. To accomplish this, the slot 10' is provided with an abutment face 13 (Figs. I and III) 105 adapted to engage the projection 9, and the slot 7 has an abutment face 13' (Figs. I and IV) adapted to engage the projection 12, said face 13' being in the form of a cam. When the projection 9 is moved upwardly 110

to the position shown by full lines in the drawings, it travels along the abutment face 13, and at the same time the projection 12 moves along the cam face 13', with the result of forcing the sashes toward each other. At this time the bolt 8 is placed under tension, and its projections 9 and 12 firmly engage the faces 13 and 13', as shown most clearly by Fig. I.

- 10 In applying the locking device to a window, the locking bolt 8 and its guide 5 can be used as a tool for screwing the tube D into the upper sash. After the upper sash has been bored to receive the threaded tube D, the locking bolt 8 is inserted into the slot 11 whereby it is interlocked with the tube D, and the guide 5 can then be turned to impart a rotary motion to the bolt 8 and tube D, thereby screwing the tube into the upper sash.

20 To prevent rotation of the tube D, the threads of said tube are provided with alined notches 15 in their peripheral edges and a pointed anchoring member 16, preferably in the form of a nail, is driven into these notches.

I claim:

1. A sash lock comprising a tubular bolt-receiving member adapted to be introduced into the upper sash of a window, a tubular guide member adapted to be secured to the lower sash, each of said tubular members being provided with an angular slot formed through the walls of said tubular members, said slots being of the same widths throughout their lengths and the slot in one of said members being provided with a cam face, and a locking bolt movable longitudinally in said tubular guide member so as to locate one of its ends in said tubular bolt-receiving member, said locking bolt having projections movable in the angular slots in said tubular members, and one of said projections being adapted to engage said cam face to force the sashes toward each other.

2. A sash lock comprising a bolt-receiving

member adapted to be introduced into the upper sash of a window, a guide member adapted to be secured to the lower sash, and a locking bolt movable longitudinally in said guide member so as to locate one of its ends in said bolt-receiving member, said locking bolt being free to turn in said guide member when said end is located in said bolt-receiving member, one of said members having a slot of constant width formed through the wall thereof, said slot comprising a portion extending longitudinally of said member and a curved portion having a cam face and said locking bolt being provided with a projection movable on said cam face when the bolt is turned in said guide member.

3. A sash lock comprising a bolt-receiving member in the form of a tube having external threads adapted to be secured into the upper sash of a window, a guide member adapted to be secured to the lower sash, a locking bolt movable longitudinally in said guide member so as to locate one of its ends in said bolt-receiving member, said locking bolt being free to turn in said guide member when said end is located in said bolt-receiving member, one of said members having a slot of constant width formed through the wall thereof, said slot comprising a portion extending longitudinally of said member and a curved portion having a cam face and said locking bolt being provided with a projection movable on said cam face when the bolt is turned in said guide member, said external screw threads on said bolt-receiving member being provided with alined notches in their peripheral edges, and a pointed anchoring member adapted to be driven into said alined notches to prevent rotation of said bolt-receiving member.

In testimony that I claim the foregoing I hereunto affix my signature.

HARRY E. ROGERS.
